UNITED STATES PATENT OFFICE.

HENRY S. DEANER, SR., OF PHILADELPHIA, PENNSYLVANIA.

HAT-PIN HOLDER AND SHEATH.

1,020,131.

Specification of Letters Patent. Patented Mar. 12, 1912.

Application filed March 9, 1911. Serial No. 613,322.

To all whom it may concern:

Be it known that I, HENRY S. DEANER, Sr., a citizen of the United States, residing in the city and county of Philadelphia, State of Pennsylvania, have invented a new and useful Hat-Pin Holder and Sheath, of which the following is a specification.

My invention consists of a hat pin holder and sheath embodying a sleeve, a guide on the inlet end thereof, and a device in said sleeve adapted to take frictional hold of the contiguous portion of the hat and prevent improper withdrawal of the pin, thus retaining the pin on the article of head wear, while the point remains within the sleeve guarded or protected without liability to contact with persons or objects adjacent to the sheath.

The invention is satisfactorily illustrated in the accompanying drawing, but the important instrumentalities thereof may be varied, and so it is to be understood that the invention is not limited to the specific arrangement and organization shown and described.

Figure 1 represents a perspective view of a sheath embodying my invention including a hat pin applied thereto. Fig. 2 represents a longitudinal section of a sheath on an enlarged scale. Fig. 3 represents a perspective view of a detached portion thereof. Fig. 4 represents a transverse section on line $x-x$ Fig. 2.

Similar letters of reference indicate corresponding parts in the figures.

Referring to the drawings, A designates a sleeve, and B designates a tubular plug which occupies the inlet end of the former and has its bore C in communication with the interior of said sleeve, its outer wall being formed with a countersink D, by which the point of a hat pin may be guided to said bore C and so caused to enter said sleeve A.

E designates a device for frictionally holding the hat pin within the sleeve, it being located within the sleeve A back of the plug B and constructed of a plate of metal or other suitable material bent and folded on itself into the form of a plurality of radiating wings F, the latter approaching each other at the center of the device forming the longitudinally-extending passage G at said center to receive the portion of the hat pin passed therethrough. The end members H of the device are disconnected and so are resilient in nature, whereby they

may expand and contract, the expansion being occasioned by the hat pin entering the passage G and separating the said members H, whereby they close on the hat pin and frictionally hold the same while the point of the pin is covered or guarded within the sleeve, it being noticed that one of the members H is shorter than the other member, so that while the larger member may contact with the sleeve A, the short member is free therefrom, and so may be removed from the long member and permit the expansion of the adjacent portions of the wings when the pin is driven through the passage G and consequently closing the wings on the pin, see Fig. 4.

On the interior of the sleeve is an inwardly extending bead J which forms a shoulder against which the inner end of the device E receives its thrust or abuts and so limits the motion of the device into the sleeve, while the outer end of the device contacts with or is adjacent to the inner end of the plug B, which is firmly secured to the sleeve and thus the device retains its position between said shoulder and plug, and the passage G registers with the bore C, it being evident that when the pin is pushed through said bore, it enters the passage G and is engaged by the walls thereof composed of the wings F and is subjected to the pressure of the end members H, so that the pin is controlled within the sleeve A and prevented from disconnection, while its point is sheathed or covered and prevented from injuring persons or objects close to the sleeve, it being evident also that the pin retains its position on a hat, bonnet or other article of head gear to which it may be applied and will not slip or disengage therefrom until superior force is imparted to the same in outward direction, when the frictional hold thereon is overcome and the pin emerges from the sleeve and so is entirely disconnected therefrom. The sleeve may have thereon an ornamental head as shown dotted in Figs. 1 and 2.

The device is applicable to pins for scarfs, jewelry and other purposes.

Having thus described my invention what I claim as new and desire to secure by Letters Patent, is:—

1. In a pin holder of the character stated, a spring composed of a single plate having a plurality of radiating wings united near the center and all diverging from the in-

ner bends of the several wings as a center and adapted to be expanded at said center by the entrance of a pin between the same, one of the wings being formed by the terminals of the plate, said terminals being separated at the outer extremity of the wing.

2. In a pin holder of the character stated, a sheath, and a spring received in said 10 sheath and composed of a plate having a plurality of radiating wings united near the inner center and all diverging from the inner bends of the several wings as a center and adapted to be expanded at said center by the 15 entrance of a pin between the same, one of the wings being formed by the terminals of the plate, said terminals being separated at

the outer extremity of the wing, and one terminal being of less length than the other.

3. A pin holder composed of a sleeve, a 20 tubular piece at the inlet thereof, a spring within said sleeve back of said piece, and a shoulder on the interior of the sleeve for the thrust of said spring in inward direction, said spring being formed of radiating wings 25 with a passage centrally between the same, said passage being in communication with the bore of the inlet piece and the interior of said sleeve, said wings being adapted to grip the pin within the passage.

HENRY S. DEANER, SR.
